AIR REGULATING MEANS FOR LIQUID
FUEL FURNACES

Harry Campbell Grant, Jr., New York, N. Y., assignor to Walter Kidde & Company, Inc., New York, N. Y., a corporation of New York

Application July 1, 1932, Serial No. 620,429

5 Claims. (Cl. 236—15)

This invention relates to means for varying the volume of air for combustion purposes supplied to liquid-fuel furnaces and the like through the medium of automatic control means actuated by the pressure of the fuel, so that proportionate quantities of fuel and air are introduced into a furnace under all variations of heat production found desirable.

More specifically, the present invention constitutes an improvement in, or rather a desirable modification of, the invention shown and described in my co-pending application for Letters Patent of the United States, Serial No. 620,430, filed on even date herewith.

In common with my herein referred to co-pending application, wherein a balancing mechanism controlled by the variable pressures of fuel and air is employed to control the supply of steam to the air delivery control means of a furnace, whereby to maintain a proper balance between the quantities of fuel and air delivered to the furnace, the present invention preferably contemplates the use of electrically operated means for translating the controlling effect of the balancing mechanism into control of the supply of steam to the air delivery control means.

In somewhat more specific terms the use of an electrically controlled motor driven valve for controlling the supply of steam to a blower engine, is contemplated, whereby to secure automatic adjustment of the forced draft of a furnace.

With such an arrangement, when some condition arises making necessary a readjustment of the forced draft, the motor driven blower valve must open or close a certain amount to re-establish a proper forced draft. In view of the fact that the fine adjustment to be made requires the use of a slow-adjusting blower valve, and in order to reduce the time necessary for the motor driven blower valve to open or close the required amount, whereby to more closely approach the desired continuous balanced condition between the quantities of fuel and air, the present invention provides, specifically, a small by-pass electro-magnetically operated valve which, when it is necessary to open the motor driven blower valve wider, opens full and gives a sudden small increase in steam to accelerate the blower more quickly, the motor driven valve continuing to open slowly to obtain a close adjustment on the forced draft. Conversely, when the motor driven valve starts to close, the electro-magnetic valve closes completely to reduce

the speed of the blower more quickly, the motor driven valve giving the final close adjustment.

It is accordingly an object of the present invention to provide, in an apparatus of the nature referred to, means to anticipate requisite increases and decreases in the quantity of actuating fluid, such as steam, supplied to the air delivery control means of a furnace.

A feature of the invention is the provision, in one specific embodiment thereof, of an electro-magnetically operated by-pass valve operating in conjunction with an electrically operated main blower valve.

It is a further object of the invention to provide, in connection with the feature just referred to, means to open or close the by-pass valves quickly and in advance of requisite degrees of opening and closing of the main valve, but subsequent to the initiation of opening and closing movements of the main valve.

These and further objects of the invention will be apparent as the same is described more fully in connection with the accompanying drawings wherein:

Figure 1 is a combined diagrammatic representation and wiring diagram of one embodiment of my invention.

Figure 2 is a somewhat enlarged view of an electro-magnetically operated by-pass valve capable of use with the present invention.

Figure 3 is a somewhat enlarged view of the means for controlling the electro-magnetically operated by-pass valve.

Referring to Figure 1, I have illustrated at A a furnace having an induced draft stack B and an air delivery duct C, the delivery of air to the latter being effected by a blower D controlled by a prime mover E in turn subject to the controlling effect of a steam supply valve F. The reference character G represents a source of steam, while H represents the fuel supply to the furnace A.

The valve I is specifically concerned with the present invention and will be referred to in detail further on in this description.

At I is shown a balance arm having a fulcrum at 2 and having suspended therefrom two air containers 3 and 4. These air containers are arranged to rise and fall within tanks 5 and 6 containing an air-sealing liquid, such as water. The interior of the air container 3 is connected by means of a pipe line 7 with the forced draft duct C, while the interior of the air container 4 is connected by means of a pipe line 8 with the induced draft stack B. At 9 is shown an expansible

- bellows-like member which is connected by a pipe line 10 with the fuel supply H and which is adapted to expand and contract upon variations in the pressure of the fuel, the movements 5 of the bellows-like member being transmitted, against the compressive force of a spring 11, to an arm 12, pivoted at 13, and connected by a link 14 with a carriage 15 supporting a number of weights 16 and adapted to be moved along the 10 balance arm 1 with the aid of a roller 17.
- The reference numeral 18 represents a contact supported on the balance arm 1 and adapted to rise and fall with the balance arm between contacts 19 and 20 arranged to define upper and 15 lower limiting positions of the balance arm. The contact 18 is electrically connected, as by a flexible connection 21, wires 22, 23, 24 and 25, fuse 26, and one side of the double pole switch 27 to the positive side of a source of electrical energy. 20 The upper contact 19 is connected by wire 28, through the coil of an electro-magnet 28' with one side of an electric limit switch assembly generally indicated as K, which will be more particularly described hereinafter. The limit 25 switch is in turn connected with the negative side of the source of electrical energy through wires 30, 31 and 32, fuse 33, and one side of the double pole switch 27. The lower contact 20 is connected through the coil of the electro-magnet 34' 30 and wire 35 to the opposite side of the limit switch K and thus is similarly connected to the negative side of the source of electrical energy by wires 30, 31 and 32, fuse 33 and the negative side of the double pole switch 27.
- 35 The limit switch K consists of a base 31' of insulating material having conducting pieces 32' and 33' pivoted thereon. The conducting pieces 32' and 33' are respectively electrically connected to the electrical leads 35 and 29. Mounted 40 on the base 31', between the conducting pieces 32' and 33', and having electrical contacts 36' and 37', is a conducting piece 35' which is electrically connected to the lead 30. The conducting pieces 32' and 33' make contact respectively with contacts 36' and 37'. The conducting piece 32' is held against contact 36' by a spring-pressed button assembly 38' mounted in the base 31', and likewise the conducting piece 33' is held against the contact 37' by the pushbutton 39'. 45 The operation of the limit switch assembly is effected by means of a slide block 40' provided with motion transmitting screw threads engaging with co-operating screw threads on the valve stem 37. The slide block 40' is provided with a depending projection 41' lying between the conducting pieces 32' and 33'. The slide block 40' is grooved as at 42' for the reception of bars 43' which are supported by the uprights 44'. By reason of this arrangement of parts, rotation of the valve stem 37 will cause the slide block 40' 50 to slide along the bars 43' and will cause the projection 41' to engage either the conducting piece 32' or the conducting piece 33', breaking the contact at either 36' or 37', depending upon the direction of rotation of the shaft 37.
- 55 The various parts of the limit switch assembly are so proportioned that, when the steam supply valve F is completely closed, the limit switch toward the valve F, i. e., the conducting piece 33', opens the contact 37', thus opening the energizing circuit of the electro-magnet 28' and preventing the valve from attempting to close further. Conversely, the limit switch towards motor 36, i. e., the conducting piece 32', when 60 engaged by the slide block to open the contact 75 36, opens the energizing circuit of the electro-magnet 34' and prevents the valve from opening further.
- In practice, the electro-magnets 28' and 34' are arranged on a single support and control a single armature pivoted intermediate of the electro-magnets and extending over the cores of both electro-magnets, as is described in my copending application Serial No. 620,430. For the present it will be sufficient to note that the energization of the electro-magnet 34' effects the making of contact at 68 and 69, while the energization of the electro-magnet 28' effects the making of contact at 70 and 71, the movable contact elements 72, 73, 74 and 75 being mounted on but electrically insulated from the armature. It will, of course, be noted that the movable contacts 72 and 73 are electrically connected, while the movable contacts 74 and 75 are similarly electrically connected.
- The fixed contacts 68, 69, 70 and 71 are mounted in any suitable manner and between the contacts 69 and 70 is connected a resistance 76, while between the contacts 68 and 71 is connected a resistance 77. A switch 78 is arranged to short-circuit the resistance 77 when desired.
- The resistances 76 and 77 are, when there is a closed electrical circuit through them, in circuits which control the blower steam supply valve F. The resistance 77 is in the circuit which controls the opening of the valve and, therefore, when it is desired to open this valve rapidly, the resistance 77 should be short-circuited by closing the switch 78. Lamps 79 and 80 are provided to indicate whether the valve F is being opened or closed.
- An electrical motor 36 is arranged to rotate the valve stem 37 in either direction through the reduction gear assembly 38, the armature leads for the motor being shown at A₁ and A₂, while the field leads are shown at F₁ and F₂, the latter being connected respectively to the positive and negative sides of the source of electrical energy by wires 39, 24 and 25, and by wires 40, 41, 31 and 32 respectively.
- In view of the fact that the apparatus as just described has been disclosed in my herein referred to co-pending application, in which its operation has been described in full, it is believed to be sufficient to point out, in so far as the present invention is concerned, that closing of the contact 18-20 effects energization of the armature of the motor 36, causing it to rotate the valve stem 37 in such a direction as to open the valve F to increase the supply of steam to the prime mover E and consequently increase the quantity and pressure of the air delivered to the furnace by the blower D, while closing of the contact 18-19 effects energization of the armature of the motor 36 with a reversed polarity, causing it to rotate the valve stem 37 in such a direction as to close the valve F to decrease the supply of steam to the prime mover E and consequently decrease the quantity and pressure of the air delivered to the furnace by the blower D.
- As a matter of interest, it should be noted that the contacts 18-20 will close to increase the forced draft upon a decrease in the induced draft, or upon a drop in the steam pressure (causing the blower to slow down), or upon an increase in the pressure of the fuel, or upon a decrease in the forced draft itself, due to the cutting in of more fires. Conversely, the upper contact 18-19 will close to decrease the forced draft upon an increase in the induced draft, or upon

an increase in the steam pressure, or upon a decrease in the pressure of the fuel, or upon an increase in the forced draft itself, due to the cutting out of fires.

5 It will therefore be seen that the arrangement just described enables a balanced condition to be maintained between the variable pressures of the fuel and air delivered to a furnace, and hence a proper balance is effected between the quantities of fuel and air delivered to the furnace.

10 With such an arrangement, when some condition arises making necessary a readjustment of the forced draft, the motor driven blower valve F must open or close a certain amount to re-establish a proper forced draft. In view of the fact that the adjustment to be made is rather fine, the blower valve F is necessarily slow-adjusting, and in order to reduce the time necessary for the motor driven valve F to open or close the required amount, so as to more closely approach the desired continuous balanced condition between the quantities of fuel and air delivered, I provide a small by-pass electro-magnetically operated valve I which, when it is necessary to open the motor driven valve F wider, opens full and gives a sudden small increase in steam to accelerate the blower D more quickly, the motor driven valve F continuing to open slowly to obtain a close adjustment on the forced draft.

15 Conversely, when the motor driven valve starts to close, the electro-magnetic valve I closes completely to reduce the speed of the blower more quickly, the motor driven valve giving the final close adjustment.

20 35 The manner of operation of the valve I can best be understood in connection with Figure 2 in which it is more clearly shown than in Figure 1. The valve I and its operating electro-magnet L are both commercially obtainable, so that it is unnecessary to show and describe them in detail herein. The valve I is shown as a simple poppet valve normally maintained in its closed position by a coiled spring and opened by depression of the valve stem 42. The electro-magnet L is shown with a base 43 on which are mounted standards 44 and 45 on which in turn are pivoted levers 46 and 47. One end of the lever 47 is pivoted on an extension on one end of the core 48 of the electro-magnet L, while its other end is pivoted to one end of the lever 46. The other end of the lever 46 is bored to receive the threaded shank 49 of the valve stem contactor 50, the position of which is adjusted with respect to the valve stem 42 by means of adjusting nuts 51 and 52. With this arrangement, energization of the electro-magnet L will cause the valve stem 42 to be depressed and the valve I opened, while deenergization of the electro-magnet will permit the valve to be closed under the influence of its coiled spring.

40 45 The manner in which the electro-magnet L is energized and deenergized will now be described in connection with Figure 3, reference being had, however, to Figure 1 also. In Figure 3 the reference numeral 53 represents the shaft of an element of the reduction gear assembly 38, said element being an intermediate element and hence having a rotative speed less than the input speed from the motor 36 but greater than the output speed to the valve stem 31, whereby the shaft 53 can be employed to effect an operation subsequent to the initiation of the operation of the motor 36, but in advance of the completion of the opening or closing movement of the valve stem 31. On the shaft 53 is mounted a disc 54 having

5 notches 55 and adapted to rotate with the shaft. Mounted below the disc 54 and on a base 56 is a standard 57 on which a rocker arm 58 is pivoted at 59. The standard 57 also supports a single pole single throw toggle switch 60 having electrical leads 61 and 62. The toggle switch 60 has the usual tiltable lever 63, and the toggle switch is so disposed that the head of the lever 63 lies between suitably formed arms 64 on the rocker arm 58. A spring 65 connected at one end to the rocker arm 58 and supported at its other end on the base 56, is provided for returning the rocker arm to its normal vertical position.

10 15 With this apparatus normally in the position shown it will be evident that rotation of the disc 54 in one direction will cause the upper end of the rocker arm 58 to leave the notch 55 and to ride upon the periphery of the disc, whereby the rocker arm 58 will carry with it the tiltable lever 63 of the toggle switch, thus operating the latter. So long as the disc 54 rotates in the same direction, or even stops, the rocker arm 58 will rest on the periphery of the disc, as only rotation in the reverse direction will enable the rocker arm to engage one of the notches 55. If, now, the direction of rotation of the disc 54 is reversed, the spring 65 returns the rocker arm momentarily to its normal position, from which it is immediately rocked to its opposite position 20 when the upper end of the rocker arm is expelled from the notch and caused to ride upon the periphery of the disc, thus causing the toggle switch to be operated oppositely to its initial operation.

25 30 35 With the foregoing construction in mind, reference should now be made to Figure 1, in which it will be seen that an initially open circuit exists from the positive side of the source of electrical energy, through one side of the double pole switch 27, fuse 26, wires 25 and 66, electro-magnet L, wire 61, lead 62, normally open switch 60, lead 61, wires 68, 41, 31 and 32, fuse 33, and the other side of the double pole switch 27 to the negative side of the source of electrical energy.

40 45 It will of course be understood that the normally open switch 60 and the rotatable disc 54 are so mounted that the switch will be closed when the forced draft must be increased, and will be opened when the forced draft must be decreased. With this in mind it will be apparent that the initiation of the rotation of the motor 36 in a direction to open the blower valve F to effect a desired increase in the forced draft, will result in energization of the electro-magnet L. This will cause full opening of the valve I which will give a sudden small increase in the supply of steam to the blower engine, whereby the blower D will be more quickly accelerated, the valve F continuing to open slowly to obtain a closer adjustment. If, now, the motor driven valve starts to close, the electro-magnetic valve I closes completely to reduce the speed of the blower more quickly, the motor driven valve giving the final close adjustment.

50 55 60 From the foregoing description it will be apparent that I have made a desirable improvement in regulating mechanisms of the type referred to and it is to be understood that the present invention, while it has been described with specific reference to the accompanying drawings, is not to be limited, save as defined in the appended claims.

65 I claim:

1. In a regulating mechanism for maintaining a balanced condition between the quantities

of fuel and air delivered to a furnace and embodying a beam balanced about a fulcrum by the variable pressures of the fuel and the air, air delivery means for delivering air to a furnace, a steam actuated prime mover for actuating the air delivery means, means to control the supply of steam to the prime mover, and means to control the last named means by movement of the beam on either side of its balanced position, said steam supply control means being operable for effecting both increases and decreases in the quantity of steam supplied to the prime mover and having a relatively slow-adjusting controlling effect, the combination of means to anticipate the requisite increases and decreases in the quantity of steam supplied to the prime mover, said last named means comprising auxiliary means acting relatively quickly to initiate or terminate an auxiliary flow of steam to the prime mover, and means actuated upon movement of the beam to operate the auxiliary means.

2. In a regulating mechanism for maintaining a balanced condition between the quantities of fuel and air delivered to a furnace and embodying a beam balanced about a fulcrum by the variable pressures of the fuel and the air, air delivery means for delivering air to a furnace, a steam actuated prime mover for actuating the air delivery means, a main valve for controlling the supply of steam to the prime mover, and means to control the main valve by actuation of the beam on either side of its balanced position, said main valve being operable for effecting both increases and decreases in the quantity of steam delivered to the prime mover and having a relatively slow-adjusting controlling effect, the combination of means to anticipate requisite increases and decreases in the quantity of steam supplied by the main valve to the prime mover, said last named means comprising an auxiliary valve having a lesser steam controlling effect than the main valve but acting relatively quickly to initiate or terminate an auxiliary flow of steam to the prime mover, and means to operate the auxiliary valve actuated subsequent to and as the result of the initiation of the operation of the means controlled by movement of the beam for controlling the main valve.

3. In a regulating mechanism for maintaining a balanced condition between the quantities of fuel and air delivered to a furnace and embodying a beam balanced about a fulcrum by the variable pressures of the fuel and the air, said beam exerting a controlling effect on the pressure of the air delivered to the furnace by relatively small movements of the beam on either side of its balanced position and between limiting positions, air delivery means for delivering air to a furnace, a fluid actuated prime mover for actuating the air delivery means, a main valve for controlling the supply of fluid to the prime mover and having a relatively slow-adjusting controlling effect, electrically operated rotary means connected to the main valve for effecting different degrees of opening and closing of the valve, said electrically operated rotary means having a relatively high rotative speed and being adapted to rotate in either direction, speed reducing means in the connection between the valve and the electrically operated rotary means and having at least one speed intermediate the input speed to the speed reducing means and the output speed from the speed reducing means, an electrical circuit for controlling the rotary means to cause it to effect an opening movement of the main valve, a sec-

ond electrical circuit for controlling the rotary means to cause it to effect a closing movement of the main valve, two electrical contacts arranged to define upper and lower limiting positions of the beam, each contact being electrically connected with a different one of the two electrical circuits, and a contact on the beam arranged to float normally between the first mentioned contacts and adapted to effect energization of either one or the other of the two electrical circuits upon contacting with either one or the other of the first mentioned contacts, the combination of means to anticipate requisite opening and closing movements of the main valve, said last named means comprising an auxiliary valve having a lesser fluid controlling effect than the main valve but acting relatively quickly to initiate or terminate an auxiliary flow of fluid to the prime mover, and means to operate the auxiliary valve actuated upon the initiation of the operation of the speed reducing means and from an intermediate speed element of said speed reducing means.

4. In a regulating means for controlling a mechanism to be operated at varying speeds by the delivery of a fluid from a source of supply and embodying a valve for controlling the supply of the fluid to the mechanism, electrically operated rotary means connected to the valve for effecting different degrees of opening and closing of the valve, said electrically operated rotary means having a relatively high rotative speed and being adapted to rotate in either direction subject to the controlling effect of a selective controlling means, and speed reducing means in the connection between the valve and the electrically operated rotary means whereby said valve has a relatively slow-adjusting controlling effect, the combination of means to anticipate the requisite opening and closing of the valve under the influence of the selective controlling means, said last named means comprising an auxiliary valve having a lesser fluid controlling effect than said valve but acting relatively quickly to initiate or terminate an auxiliary flow of fluid to said mechanism, said auxiliary valve being adapted for electro-magnetic operation, and an electrical circuit for effecting operation of the auxiliary valve and including a contact actuated subsequent to and as the result of the initiation of the aforesaid electrically operated rotary means under the control of the aforesaid selective controlling means.

5. In a regulating mechanism for maintaining a balanced condition between the quantities of fuel and air delivered to a furnace and embodying a beam balanced about a fulcrum by the variable pressures of the fuel and the air, air delivery means for delivering air to a furnace, a fluid actuated prime mover for actuating the air delivery means, a main valve for controlling the supply of fluid to the prime mover and having a relatively slow-adjusting controlling effect, electrically operated means for effecting different degrees of opening and closing of the main valve, an electrical circuit for controlling the electrically operated means to cause it to effect an opening movement of the main valve, a second electrical circuit for controlling the electrically operated means to cause it to effect a closing movement of the main valve, two electrical contacts arranged to define upper and lower limiting positions of the beam, each contact being electrically connected with a different one of the two electrical circuits, and a contact on the

beam arranged to float normally between the first mentioned contacts and adapted to effect energization of either one or the other of the two electrical circuits upon contacting with either one or the other of the first mentioned contacts, the combination of means to anticipate requisite opening and closing movements of the main valve, said last named means comprising an auxiliary valve having a lesser fluid controlling ef-

fect than the main valve but acting relatively quickly to initiate or terminate an auxiliary flow of fluid to the prime mover, and means to operate the auxiliary valve actuated subsequent to and as the result of the initiation of the operation of the electrically operated means for effecting different degrees of opening and closing of the main valve.
